UNITED STATES PATENT OFFICE.

HERBERT S. JANDUS, OF KALAMAZOO, MICHIGAN, ASSIGNOR TO THE C. G. SPRING & BUMPER COMPANY, OF DETROIT, MICHIGAN, A CORPORATION OF DELAWARE.

BUMPER.

Application filed December 7, 1922. Serial No. 605,500.

This invention relates to bumpers, and more particularly to bumpers of the type disclosed and claimed in the patent of Allan L. McGregor, No. 1,372,154 issued 5 March 22, 1921. The general object of the invention is to provide a bumper having the capability of protecting in a most efficient manner the vehicle to which it is attached and of its withstanding severe impacts received by any portion thereof. More limitedly, the invention contemplates providing a bumper of the character referred to with a construction and arrangement of the lateral ends thereof that will secure a maximum 10 degree of flexibility in these portions of the bumper, and which will enhance the appearance of such ends. I accomplish the foregoing object and other objects which will appear hereinafter in and through the construction and arrangement of parts illustrated in the drawings forming a part hereof, wherein Fig. 1 represents a plan view of a bumper constructed in accordance with my invention and of the cooperating ends 15 of its supporting members; Fig. 2 a front elevation of the said bumper; and Fig. 3 a detail in perspective of the end portions of the bars or members of the bumper, showing the same in vertically separated relation.

Describing the various parts herein by reference characters, 1 denotes a pair of supporting arms which are adapted to be connected at their rear or inner ends to the adjacent ends or portions of the side frames. 20 For convenience of description, the bumper will be assumed to be secured to the front of the automobile, and the terms "front" and "rear" will be used accordingly, but without limiting the use of the invention to such front portion of the automobile, it being obvious that it may also be applied to the rear of the same by merely reversing the positions of the bumper and of its supporting arms.

45 The bumper itself comprises, in general, a front or impact member consisting of a pair of vertically spaced bars 2 each extending throughout the full length of the bumper and spaced apart vertically in parallel relation.

50 Each end of each of the bars 2 is bent rearwardly and then inwardly, to provide an outwardly or forwardly convex end portion 2^a, and a short inwardly extending end portion 2^b, there being a short loop 2^c pro-

vided between the portions 2^a and 2^b. The extreme ends of each of the bars 2 are deflected forwardly, as shown at 2^d, toward the front or impact portion of such bar and are provided at their extreme ends each 60 with an eye 2^e.

3 denotes a rear bar, the same having a central V-shaped portion 3^a which is interposed between and connected to the central portions of the bars 2 by means of any suitable clamping device, such as a bolt 4 having plate-engaging members 4^a and 4^b thereon, the members 4^a engaging the top of the uppermost and the bottom of the lowermost bar, respectively, while the members 4^b engage the adjacent edges of the intermediate bar and of the top and bottom bars, respectively. From this V-shaped central portion, there extend outer end portions 3^b, substantially parallel with the corresponding portions of the front or impact members 2. The outer ends of the parts 3^b extend between and in line with the parts 2^b of the bars 2 and are bent outwardly and inwardly in vertical alignment with the parts 2^a, as indicated at 3^c, the extreme ends being bent rearwardly, as shown at 3^d, and each being provided with an eye 3^e adapted to align with the eyes 2^e. The ends of the bars 2 are thus provided each with a rearwardly directed loop terminating in an eye, while the ends of the bar 3 are provided each with a forwardly directed loop terminating in an eye. The ends of the bars are connected by bolts 5 extending through the aligned eyes 2^e and 3^e, there being spacing washers between the bars, as indicated at 6.

Adjustably mounted upon each part 3^b of the rear or auxiliary section of the bumper is a clamp 7, which clamps may be of any desired construction, each being shown as pivotally connected to a supporting arm 1 by means of a vertical bolt 8.

When the parts of the bumper are assembled, there results therefrom a bumper having a plurality of front or impact bars vertically spaced and aligned, with an intermediate rear or auxiliary bar connected at its central portion and at its ends to the ends of the impact portion or section, the bumper having looped ends which not only present an extremely attractive appearance, due to the shape of such ends and to the vertical alignment of the loops at both ends thereof, but which materially increase the 100 105 110

resiliency of the bumper and of the end portions thereof—particularly over a construction wherein the ends are connected without such loops.

Having thus described my invention, what I claim is:

1. In a bumper, the combination of an impact section comprising a pair of bars having their ends vertically spaced, the end portion of each bar being bent rearwardly, inwardly and forwardly and each provided at its extreme end with an eye, and a rear or auxiliary bar spaced at its end portions from and at the rear of the corresponding portions of the first mentioned bars, each end of such rear or auxiliary bar being bent forwardly and inwardly and rearwardly and provided at its extreme rear end with an eye adapted to align with the eyes at the corresponding ends of the first mentioned bars, the eyes of the third bar being interposed between the eyes on the corresponding ends of the first two bars, and securing means extending through and uniting said eyes.
2. In a bumper, the combination of an impact section comprising a pair of bars extending substantially the length of the bumper and having their ends vertically spaced, the end portions of each bar being bent rearwardly, inwardly and forwardly and each provided at its extreme end with an eye, and a rear or auxiliary bar also extending substantially the length of the bumper and spaced at its end portions from and at the rear of the corresponding portions of the first mentioned bars, each end of such auxiliary bar being bent forwardly and inwardly and rearwardly and provided at its extreme rear end with an eye interposed between and arranged to align with the eyes at the corresponding ends of the first mentioned bars, and securing means extending through and uniting said eyes.
3. In a bumper, the combination of an impact section comprising upper and lower bars each having a looped end terminating in an eye, and a rear or auxiliary section comprising a bar having at each end an eye adapted to be interposed between the eyes on the corresponding ends of the first mentioned bars, and means extending through said eyes for connecting the ends of said bars.
4. In a bumper, the combination of an impact section comprising upper and lower bars each having a rearwardly extending inwardly and forwardly looped end portion, and a rear or auxiliary section comprising a bar having ends adapted to be interposed between the corresponding ends of the first mentioned bars, and means connecting the ends of said bars.
5. In a bumper, the combination of a front or impact section comprising upper and lower bars each having its ends formed into

rearwardly extending loops, the loops at corresponding ends being in vertical alignment and the extreme ends of the said bars being provided with aligned eyes, and a rear or auxiliary bar adapted to be secured at its central portion to the central portions of the first mentioned bars and having portions extending substantially parallel with the end portions of the first mentioned bars and end portions formed into forwardly extending loops adapted to align with the loops at the corresponding ends of the first mentioned bars and having at their extreme ends eyes adapted to align with the eyes on the corresponding ends of the first mentioned bars. 80

6. In a bumper, the combination of a front or impact section comprising upper and lower bars each having its ends formed into rearwardly extending loops, the loops at corresponding ends being in vertical alignment and the extreme ends of the said bars being provided with aligned eyes, and a rear or auxiliary bar having its end portions formed into forwardly extending loops adapted to align with the loops at the corresponding ends of the first mentioned bars, and means for securing together the aligned ends of said bars. 90

7. A vehicle bumper comprising a front or impact bar adapted to extend across an end of the vehicle and having each end portion formed into a rearwardly and inwardly extending loop, a rear or auxiliary bar spaced at its end portions from the end portions of the first mentioned bar and having such portions bent into forwardly and inwardly extending loops adapted to align with the loops at the corresponding ends of the first mentioned bar, and means for securing the ends of said bars together. 100

8. A vehicle bumper comprising a front or impact bar adapted to extend across an end of the vehicle and having a rearwardly and inwardly extending loop at each end thereof, a rear or auxiliary bar spaced at its end portions from the end portions of the first mentioned bar and having its ends bent into forwardly and inwardly extending loops adapted to align with the loops at the corresponding ends of the first mentioned bar, the said loops terminating in eyes, and bolts extending through the eyes at each end of the bumper structure. 110

9. In a bumper, the combination of a pair of vertically spaced bars adapted to extend across an end of the vehicle and each having its end bent rearwardly, inwardly, and forwardly to form a loop, a rear or auxiliary bar also adapted to extend across such end of the vehicle and having each of its ends bent forwardly, inwardly and rearwardly to form a loop, the said bars being provided with eyes at their ends, the eyes on the ends of the third bar being located between the eyes at the ends of the first two bars, and 130

means extending through and connecting the eyes at each end of the bumper structure.

10. In a bumper, the combination of a pair of vertically spaced bars adapted to extend across an end of the vehicle and each having its end portions bent to form each a rearwardly extending loop, a rear or auxiliary bar also adapted to extend across such end

of the vehicle and having each of its end portions formed into a forwardly extending ¹⁰ loop, and means for connecting the ends of the loops at each end of the bumper.

In testimony whereof, I hereunto affix my signature.

HERBERT S. JANDUS.
